CURTAIN ROD

Graham B. Waddell, Mount Lebanon, Pa.

Application July 14, 1943, Serial No. 494,679

2 Claims. (Cl. 211—105.6)

The invention relates to a curtain rod and more particularly to a double hanger type of curtain rod.

The primary object of the invention is the provision of a rod of this character wherein the same can be securely fastened to a door or window frame, the fastening thereof being had in a novel manner, so that curtains can be hung therefrom, the said rod being susceptible of adjustment to accommodate it to different sizes of window or door frames or other place of hanging thereof.

Another object of the invention is the provision of a rod of this character wherein the attaching means for the rod proper enables the firm and easy securing thereof in place and also is effective for the application and removal of curtains in a convenient manner.

A further object of the invention is the provision of a rod of this character which is simple in its construction, thoroughly reliable and effective in operation, strong, durable, readily and easily applied and removed and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention and pointed out in the claims hereunto appended.

In the accompanying drawing:

Figure 1 is a plan view partly broken away of the curtain rod constructed in accordance with the invention and in an applied position.

Figure 2 is a front view thereof showing by full lines the set position of the rod and by dotted lines adjustment thereof.

Figure 3 is a front view of the fastening medium for the rod.

Figure 4 is an elevation of one of the hanger members of the rod.

Figure 5 is a front view of a modified form of fastener.

Figure 6 is a sectional view taken on the line 6—6 of Figure 5, looking in the direction of the arrows.

Figure 7 is a side elevation of another modification of fastening medium for the rod.

Similar reference characters indicate corresponding parts throughout the several views in the drawing.

Referring to the drawing in detail, A designates generally a portion of a window or door frame for the application or mounting of the

curtain rod constituting the present invention and hereinafter fully described.

The curtain rod preferably consists of a pair of lug members 10, these being formed with internally threaded sockets 11 each opening through one end thereof and a screw hole 12 aligned with said socket. The screw hole 12 receives a wood screw 13 which fastens the lug member 10 securely to the window or door frame

10 A as disclosed in Figure 1 of the drawing.

Adapted for threaded engagement in the lug members 10 are the threaded terminals 14 of substantially L-shaped brackets or arms 15, these being disposed opposite each other and slidably 15 engageable upon such brackets or arms 15 is a tubular sleeve 16 which with the brackets constitutes the hanger for a curtain or curtains and also a single rod.

In the application of the brackets or arms 15 20 the sleeve 16 is moved to disengaging position on one of the same and thereafter both of these brackets or arms 15 are screwed into the lug members 10, and when the same are brought to have their end portions aligned with each other, 25 the sleeve 16 can be shifted for the interlocking of said brackets or arms 15, as clearly shown in Figure 1 of the drawing.

Adapted to be associated with these brackets or arms 15 and the sleeve 16 heretofore referred 30 to is a second hanger for a curtain or curtains and it includes the brackets or arms 17, the sleeve 18 and the screw threaded laterally extending eye terminals, these being extensions of the brackets or arms 17. The eye terminals 19 are 35 threaded onto the threaded ends 14 of the brackets or arms 15 prior to the engagement of such ends 14 in the stud members 10. The sleeve 18 is manipulated similarly to the sleeve 16 when alignment of the brackets or arms 17 is had as 40 shown in Figures 1 and 2 of the drawing.

In Figures 5 and 6 of the drawing there is shown a slight modification of a lug member wherein it is in the form of a flat faced head 20 having a central wood screw shank 21 and such 45 head 20 has a screw threaded socket 22 therein. The flat faced head 20 enables a wrench or other tool to be applied for the fastening of the screw shank 21 in a support.

In Figure 7 of the drawing there is shown a 50 further modification of lug member wherein the head 23 is formed with the screw shank 24 being provided with a blunt end in contradistinction to the pointed end of the screw shank 21.

By reason of the construction hereinbefore described, the rod including both the inside one

and outside one as illustrated in Figure 1 of the drawing can be readily fixed in place and taken down with ease and also the said rods proper will be prevented from being sprung or bent.

Preferably the sleeves 16 and 18 respectively can be provided with springs 25 and 26 respectively, these working against the parts 15 and 17 and function to center the said sleeves as should be obvious.

What is claimed is:

1. A curtain rod comprising a pair of lug members, means fastening the lug members to a support, the lug members being provided with threaded sockets, arms, bent at one end and threaded into the sockets, a coupling sleeve re-

leasably telescoped upon said arms, a pair of auxiliary arms having bent ends provided with threaded eye terminals engaged with the first mentioned arms, and a coupling sleeve releasably telescoped upon the second named arms.

2. A curtain rod comprising a pair of lug members, means for fastening the lug members to a support, the lug members being provided with threaded sockets, a pair of brackets having bent ends threaded into the sockets, a second pair of brackets connected to the bent ends of the brackets of said first pair, and a coupling sleeve releasably telescoped upon the brackets of each pair.

15 GRAHAM B. WADDELL.
